J. R. REPOGLE

VALVE MECHANISM

Filed May 2, 1921

UNITED STATES PATENT OFFICE.

JOHN R. REPLEGLO, OF DETROIT, MICHIGAN, ASSIGNOR, BY MESNE ASSIGNMENTS, TO ELECTRIC REFRIGERATION CORPORATION, OF DETROIT, MICHIGAN, A CORPORATION OF MICHIGAN.

VALVE MECHANISM.

Application filed May 2, 1921. Serial No. 466,262.

This invention relates in general to valve mechanism for controlling the flow of a fluid through a passage and more particularly to valves and valve operating mechanism employed in mechanical refrigerators and the like for automatically controlling the flow of a fluid into a receptacle.

One of the objects of the invention is the provision of an improved valve that does not require accurate aligning of the parts and has associated therewith improved means for automatically operating the same.

Another object of the invention is the provision of an improved valve whereby a comparatively large passage for the fluid may be employed to thereby eliminate the danger of the passage becoming obstructed by impurities contained in the fluid passing therethrough.

A still further object of the invention is the provision of valve mechanism that is simple in construction, cheap to manufacture, easily assembled, not likely to get out of order, and that will perform the additional function of a safety valve.

Other and further objects and advantages of the invention will appear as the description proceeds.

For convenience of illustration and description, the invention is disclosed only in connection with the evaporator or vaporizer element of a mechanical refrigerator, although it is understood that it is capable of use in other relations. The vaporizer shown is of the character of that disclosed in my pending applications Serial No. 448,331 filed February 28, 1921, and Serial No. 475,344, filed June 6, 1921, to which reference may be had for the details of the refrigeration system, and in which are claimed the vaporizer features, as distinguished from the valve mechanism, per se, herein claimed.

On the drawing:

Fig. 1 is a side elevation of a vaporizer element, parts in section and parts broken away;

Fig. 2 is an enlarged view of a portion of Fig. 1, with parts modified; and

Fig. 3 is a detail view of a modified form of the valve and parts of the operating mechanism.

Fig. 4 is a section on the line 4—4, Fig. 2. On Figs. 1 and 2 of the drawing, the nu-

meral 5 designates the vaporizer which may be of any well known construction. As shown, it consists of the header or expansion tank 6, having the expansion coils or loops 7 associated therewith. These expansion loops or coils may be immersed in a tank 8 containing a heat conducting medium which has a comparatively low freezing point, such as calcium chloride. The tank 8 may be provided with recesses 9 for the reception of containers or trays 10 for containing substances to be frozen, as is common in such constructions.

The vaporizer is provided at any suitable place with an inlet and an outlet passage arranged one above the other; and my improved valve mechanism is adapted to be associated with the lower or inlet passage. As shown, the header or expansion tank 6 is provided with the removable head or end piece 11 having the upper and lower passages 12 and 13, respectively, therein. The head or end pieces 11 may be secured to the expansion tank by any suitable means such as the bolts 14. Attached to the head or end piece 11 and extending inwardly from the passage 12 is the baffle pipe or tube 15 which has a closed inner end, and is provided with the horizontal opening 16 on its upper side. The bottom of this pipe or tube constitutes a baffle to prevent liquid refrigerant from being thrown into the outlet passage by the ebullition of the same.

A pipe or tube, not shown, is adapted to connect the passage with the low pressure side of the compressor. The lower passage 13 is adapted to be connected with the high pressure side of the operating mechanism by means of a tube or pipe, not shown, which is adapted to be attached at one end to the condenser and at its other end to the pipe connector 19.

The end piece or head 11 is provided with an inwardly extending projection 17 having a passage 130 therein, which consists of the recess 13^a and a laterally extending aperture 18 on its lower side. The outer end of the passage 130 is screw-threaded for the reception of the screw threads on the inner end of the connector pipe 19. The inner end of the pipe connector 19 is provided with an internal annular shoulder 20 against which is adapted to seat the outer end of a strainer 21 located in the recess 13^a. This

strainer 21 is adapted to prevent the impurities in the refrigerant from passing into the aperture 18 and thus interfering with the operation of the valve and the passage of refrigerant therethrough. The lower end of the aperture 18 is enlarged as at 18^a to form a retaining wall for a ball valve 22 of any suitable material, such as Monel metal, which is adapted to seat against the lower end of the aperture 18 and is held in position by means of a valve, or ball-retaining spring 23 which is secured to the float lever 24 by any suitable means such as a bolt 25. It will be noted that the ball valve does not require any accurate fitting or adjusting of the parts to secure it in operative position on the device.

The operation of the valve 22 is controlled by means of a float 26 which is pivotally connected at its central portion as at 27 to the float lever. By pivoting the elongated float at its central portion it will always remain horizontal and consequently the flotation leverage will remain comparatively constant.

The float 26 is preferably of metal and may consist of the cylindrical body portion 28 and the curved or hemispherical end portions 29 and 30. The end portions are set 30 cured to the reduced ends of the body portion in any suitable manner, as by soldering.

The float lever consists of a member having arms or bifurcated portions 31 and 32 between which the float 26 is pivoted. The other end of the float lever 24 is also bifurcated and is pivoted to the projection 17 on the end piece 11, as at 33. The web 34 connecting the two bifurcations, arms, or sides of the float lever is provided with a depending portion 35 at each side thereof for the reception of the ball retaining spring 23 to prevent lateral movement of the same without interfering with its flexing.

Means are provided for limiting the vertical movement of the float lever 24. This means may consist in providing a horizontal slot 36 in the upwardly extending projection 37 of the float lever 24 at each side thereof, thus forming the upper and lower shoulders 36^a and 36^b, respectively. A pin 38 carried by the projection 17 is adapted to be engaged at its projecting ends by the upper and lower shoulders of the slots 36 to thus limit the vertical movement of the lever 24.

In the operation of the device, the liquid refrigerant entering through the pipe 19, recess 13^a and aperture 18 will cause the float 26 to rise, which in turn will cause the spring 23 to seat the ball 22 in the outer end 60 of the aperture 18 to close the same. When the valve 22 is closed, under normal conditions, the liquid refrigerant cannot pass through the aperture 18. If for any reason, however, the pressure in the compressor 65 should rise above a certain point, the spring

23 will permit discharge of the refrigerant into the header or expansion tank to thus equalize the pressure and thus eliminating the use of an additional safety valve. This is an important feature of my invention. 70 As the float rises, the shoulder on the float lever 24 comes in contact with the pin 38 and limits any further upward movement of the float 26 and consequently limits the tension that may be placed on the valve 75 spring 23 so that the valve 22 will be opened by excessive pressure under any and all conditions. It also prevents the float from coming in contact with the upper wall of the header, and thus eliminates all possible 80 danger of injury to the same by such contact.

When the compressor begins to operate it soon draws sufficient vaporized refrigerant from the header to lower the float and thus 85 open the valve 22. The float is limited in its downward movement by the shoulders on the lever 24 coming in contact with the pin 38. The parts are so arranged that when the lever 24 is at its lower limit the valve 22 90 will be opened but will be held from becoming displaced and will be held in such proximity to its seat that any back pressure will seat the valve and retain the refrigerant in the header. This is an important 95 feature since it will permit the removal of the strainer for cleaning, or any other purpose, without danger of leakage of the refrigerant through the valve opening.

The valve is shown as being used in connection with that form of refrigerators in which the lubricant circulates with the refrigerant and in which the refrigerant is heavier than the lubricant. In order that the controlling mechanism for the valve 100 shall function properly, it is necessary that the float be so calibrated that it will float approximately at the intersection of the oil and refrigerant. The oil being lighter than the refrigerant will, at intervals, overflow 105 the end of the baffle pipe or plate 15 and passing down through the opening 16 will find its way back to the crank case and compressor.

In Fig. 2 is shown a modified form 115 of the baffle pipe or plate 15. In this form of the device the pipe extends at an angle inwardly and upwardly. This arrangement provides a greater space for the operation of the float. The pipe 15^a is provided with 120 apertures 39 through which the oil may pass from the header into the passage 12.

In Fig. 3 is shown a modified form of the valve and springs associated therewith. In this form of the device, aperture 18^a is provided with a valve seat 40 of any suitable material such as Monel metal. A light spring 41 tends to hold the valve 22 against its seat at all times. The spring 23^a carried by the lever 24 performs substantially the 130

same function as the corresponding spring 23 in Fig. 2. The light spring permits the refrigerant to pass the valve 22 when the float is lowered but maintains the valve seated under normal conditions so that the strainer 21 may be removed for cleaning without danger of escape of the refrigerant from the header or expansion tank.

It is thought from the foregoing, taken in connection with the accompanying drawings, that the construction and operation of my device will be apparent to those skilled in the art and that various changes in size, shape and proportion and minor details of construction may be made without departing from the spirit and scope of the invention as set forth in the appended claims.

I claim:

1. In a device of the class described, a member formed with a passage, a valve for controlling said passage, a bifurcated lever, an elongated float pivotally connected at its central portion between the bifurcations of said lever, means for pivotally supporting said lever, stop means for limiting the movement of said lever and spring means carried by said lever for operating the valve, substantially as shown and described.

2. In a device of the class described, a member provided with a passage adapted to connect the high and low pressure sides of a refrigerant system, a valve for closing said passage, a float controlled lever, stops for limiting the movement of said lever, resilient means associated with said lever for closing said valve when the float is moved in one direction, said parts being so constructed and arranged that when the valve is opened it will be held by the spring in such proximity to its seat that back pressure from the low pressure side of the system will automatically close the same and that when the valve is closed excessive pressure on the high pressure side of the system will automatically open the same, substantially as shown and described.

3. In a device of the class described, a member provided with a passage adapted to connect the high and low pressure sides of a refrigerant system, a valve for closing said passage, a float controlled lever, stops for limiting the movement of said lever, resilient means associated with said lever for closing said valve when the float is moved in one direction, said valve being free to rotate relative to said lever, said parts being so constructed and arranged that when the valve is open it will be held in such proximity to its seat that back pressure from the low pressure side of the system will automatically close the same, and that when the valve is closed excessive pressure on the high pressure side of the system will automatically open the same, substantially as shown and described.

4. In a device of the class described, a head for an expansion tank, an inwardly extending projection carried by said head and provided with a passage therethrough, the inner end of said passage being enlarged to provide retaining walls, a ball valve for closing said passage, a lever pivoted to said projection, a float for operating said lever, a flat spring carried by said lever for engaging said ball to retain the same within said walls and for closing said valve, said spring permitting excessive pressure to open said valve, and stops for limiting the movement of said lever whereby the ball valve is retained in proximity to its seat to prevent back flow, substantially as shown and described.

5. In a device of the class described, a support formed with a passage and a valve seat, a valve arranged to cooperate with said seat, a bifurcated lever, an elongated float pivotally connected at its central portion between the bifurcations of said lever, means for pivotally connecting said lever to said support, stop devices for limiting the movement of said lever, and means comprising a spring carried by said lever for operating the valve.

6. In a device of the class described, a member provided with a passage for the flow of fluid and a valve seat, a valve to control the flow of fluid through said passage arranged to close against the flow, a float-actuated lever, a spring arranged to be moved by the lever and engaging the valve to move it towards its seat, and stop devices associated with said lever to limit the opening movement of the valve and maintain it at all times in sufficiently close proximity to its seat so that back pressure will automatically close it.

7. In a device of the class described, a member provided with a passage for the flow of fluid and a valve seat, a valve to control the flow of fluid through said passage arranged to close against the flow, a float-actuated lever, a spring carried by said lever to engage the valve and move it towards its seat, and stop devices associated with said lever to limit the opening movement of the valve and maintain it at all times in sufficiently close proximity to its seat so that back pressure will automatically close it.

8. In a device of the class described, a member formed with a passage for the flow of fluid and a valve seat, a valve arranged to close against the flow, a strainer in the passage on the inlet side of the valve, and means comprising a float for actuating the valve and adapted at all times to maintain it in sufficiently close proximity to the seat to insure its closure when pressure on its outlet side exceeds that on its inlet side, whereby the passage is automatically closed when it is desired to remove the strainer.

9. In a device of the class described, a

member formed with a passage for the flow of fluid and a valve seat, a valve arranged to close against the flow, a strainer in the passage on the inlet side of the valve, and means 5 comprising a float and a spring interposed between the float and the valve for operating the valve, said operating means being adapted to maintain the valve at all times in suf-

ficiently close proximity to its seat to insure its closure when pressure on its outlet side 10 exceeds that on its inlet side, whereby the passage is automatically closed when it is desired to remove the strainer.

In testimony whereof I affix my signature.

JOHN R. REPLOGLE.
